INVENTOR.
Leo G. Haase.
BY
Friedrich Rhey
ATTORNEY

UNITED STATES PATENT OFFICE.

LEO G. HAASE, OF PASADENA, CALIFORNIA.

POST.

1,392,577.

Specification of Letters Patent.

Patented Oct. 4, 1921.

Application filed November 15, 1920. Serial No. 424,072.

To all whom it may concern:

Be it known that I, LEO G. HAASE, a citizen of the United States, and a resident of Pasadena, in the county of Los Angeles and

5 State of California, have invented certain new and useful Improvements in Posts, of which the following is a specification.

This invention relates to a post of the character employed in building fences or for 10 any other purpose where it is necessary to have a member partially embedded in the earth.

An object of the invention is to make a post of two different materials, wood for 15 the section extending above the earth and cement for the portion embedded in the earth.

Another object is to produce a post of this character of extreme simplicity of construction.

Another object is to so construct the post that it will be of maximum strength.

Another object is to make provision for a strong connection between the wood and cement sections.

Another object is to prevent the post from being withdrawn from the earth and also to prevent lateral movement.

Another object is to construct the post in 30 such a manner that the cement sections, as well as the wood sections, can be readily stacked one on top of the other for shipment and storage, so as to occupy a minimum space.

35 Another object is to make provision whereby drying out of the wood section will not produce looseness between it and the cement section.

The accompanying drawings illustrate the 40 invention:

Figure 1 is a front elevation of a post constructed in accordance with the provisions of this invention;

Fig. 2 is a side elevation of the post shown 45 in Fig. 1 from the right thereof; and

Figs. 3 and 4 are plan sections on lines indicated by x^3-x^3 and x^4-x^4 , respectively, Fig. 1.

The post comprises a wood section or 50 member 1 and a cement section or member 2. The cement section may be provided with the usual metal reinforcement members indicated at 3, 4. The cement section 2 in cross section is channel shaped, the web being indicated at 5 and the flanges at 6. In cross section the section 1 is rectangular and

of such dimensions as to loosely fit in the groove 7 of the cement section. The section 1 is inserted for a short distance in the channel 7 and is secured by bolts 8 which pass 60 through both post sections, the nuts 9 of the bolts preferably being at the rear face of the cement section.

The side portions of the channel 7 are reduced in depth by fillets 10, so that the section 1 will contact at its inner corners with the bottom of the groove and be spaced from the bottom of the groove nearer its median line. When the bolts 8 are drawn up tight 65 they spring the section 1 at its middle portion toward the bottom of the groove and, consequently, when the section 1 dries out 70 in the course of time the section 1 will still be under some tension and, therefore, securely held by the bolts.

The rear face of the section 2 is preferably convex, as indicated at 11, so that when a post section 2 is superposed upon another similar section the middle portion of the convex face 11 will rest in the groove 7 and 80 thus tend to prevent the cement sections from moving out of alignment with one another.

The lower end of the groove 7 is closed 85 by a cross member 12, and the outer face of said cross member is concave, as indicated at 13, so that when cement sections are superposed, as mentioned above, the convex face 11 will fit the concave face 13.

When the fence or other structure is to be 90 built, the post sections 1, 2, will be assembled and the cement sections will be inserted in the holes, prepared for them in the earth, to a plane just beneath the lower end of the section 1, so that after the hole is 95 filled with earth the earth will not contact with the wood section. Thus the cement section will protrude for a short distance above the surface of the earth. When thus placed in the earth, the flanges 6 will tend 100 to prevent edgewise movement of the post and the earth resting upon the cross member 12 will effectually prevent withdrawal of the post from the earth.

When the sections 1, 2, are properly assembled there will be a certain amount of buckling of the wood section sufficient to draw the head of the bolt and the nut 9 tightly against the sections 1, 2, respectively; and when the wood section dries out 110 and, therefore, contracts such contraction will not be sufficient to entirely remove the

tension in the wood section and, consequently, the bolts 8 will not become loose and the sections will, therefore, continue to be securely fastened to one another without 5 any looseness at the joint.

I claim:

1. In a post, a cement member having a longitudinal groove of less depth nearer the sides than nearer the middle portion thereof, 10 a second member inserted part way into the groove and having its inner corners resting upon the bottom of the groove and having its middle portion spaced from the bottom of the groove, and bolts passing through the 15 middle portion of the second member and into the first member.
2. In a post, a cement member having a

longitudinal groove, fillets in the corners of the groove, a second member inserted part way in the groove and having its inner corners seating against the fillets, and means to hold the middle portion of the second member toward the bottom of the groove. 20

3. In a post, a cement member, a second member, bolts connecting the members, and 25 means coöperating with the bolts to produce buckling of the second member when the bolts are drawn up tight.

Signed at Los Angeles, California, this 8th day of November, 1920.

LEO G. HAASE.
